(57) **CLAIM**

The ornamental design for bathing suit with rear openings, as
shown and described.

DESCRIPTION

The sole FIGURE is a rear elevational view of a bathing suit
with rear openings showing my new design.

The uniformly spaced broken lines on the surface of the
bathing suit represent stitching. The dot-dash broken lines
mark the boundary of the claimed design. The remaining
broken lines, showing a waistband and portion of the human
form, show details which form no part of the claim.
